UNITED STATES PATENT OFFICE.

ALVA L. EAST, OF DOWAGIAC, MICHIGAN, ASSIGNOR OF ONE-HALF TO GLENN W. MEAD, OF DOWAGIAC, MICHIGAN.

BOX.

1,000,243.

Specification of Letters Patent.

Patented Aug. 8, 1911.

Application filed December 31, 1910. Serial No. 600,289.

To all whom it may concern:

Be it known that I, ALVA L. EAST, a citizen of the United States, residing at Dowagiac, Cass county, Michigan, have invented 5 certain new and useful Improvements in Boxes, of which the following is a specification.

This invention relates to improvements in boxes.

10 The main objects of this invention are: First, to provide an improved box for use as a berry box or the like, which may be shipped in the flat or knock-down, and may be readily and quickly assembled by the 15 user. Second, to provide an improved box adapted to be made of light material, such as light paper board, or the like, which may be shipped or stored in the flat or knock-down, and assembled without stapling or 20 gluing, and when assembled, is strong and rigid. Third, to provide an improved box which is very economical in structure and which is formed of cheap material, and may be formed by a comparatively simple machine and with practically no waste of material.

Further objects, and objects relating to structural details, will definitely appear from the detailed description to follow.

30 I accomplish the objects of my invention by the devices and means described in the following specification.

The invention is clearly defined and pointed out in the claim.

35 A structure which is a preferred embodiment of my invention is clearly illustrated in the accompanying drawing, forming a part of this specification, in which:

Figure 1 is a perspective view of my improved box. Fig. 2 is a vertical central section thereof. Fig. 3 is a plan of the side wall blank. Fig. 4 is a plan of the bottom blank.

40 In the drawing, similar reference numerals refer to similar parts throughout the several views.

Referring to the drawing, the side walls are formed of the blank shown in Fig. 3, which has five side wall portions, as 1, 2, 50 and 3. The blank is preferably formed of paper board, scored at 4, to facilitate folding, the blank being bent on these scoring lines when the box is set up.

55 The end portions 3 of the side wall members are overlapped, as is clearly shown in

Figs. 1 and 2. These end wall portions 3 and the central portion 1 are provided with horizontal slits 5, the slits in the end wall portion 3 registering when the box is set up.

I provide circular openings 6 at the ends 60 of the slits, which permit the portions of the walls immediately above and below the slits to be deflected easily, and also, these circular openings prevent to a large extent tearing at the ends of the slits. The bottom 65 is formed of a blank, consisting of a bottom portion 7 and side wall portions or members 8, 8, the blank being scored at 9 to facilitate the side wall members, the side wall members being on opposite edges of the 70 bottom. These side wall members 8 have V-shaped slits 10 therein, to provide downwardly-projecting V-shaped tongues 11, which are, when the box is erected, passed through the slits 5 in the side walls, one of 75 the tongues being passed through both of the slits in the overlapped end portions, as shown in Fig. 2. Circular openings 12 are preferably formed at the ends of the slits 10, so that the tongues are more readily deflected and enter and engage the slits more 80 effectively, and also so that the blank is less likely to be torn at the end of the slits when the parts are assembled.

The bottom 7 is formed so that it fits the 85 side walls and serves to brace and support the same and is suspended a little above the bottom edge of the said side walls. The side members 8 on the bottom 7 are also of such size that the edges fit into the corners 90 of the side walls and brace and support the same.

My improved box is readily assembled without tools, and when set up, is very secure. The blanks are formed without waste 95 of material, and can be formed by very simple machines. The box when set up is braced and secured so that it can be formed of quite light material and still be very strong and rigid.

I have shown my improvements as embodied in a berry box, although it is adapted for various other purposes. When formed of paper board and adapted for use as a berry box, or the like, the inner side 105 of the box is preferably paraffined or treated with some water-proofing material, which can be done when the material is in the flat or before forming the blanks.

Having thus described my invention, what 110

I claim as new and desire to secure by Letters Patent is:

A box comprising side walls formed of a blank scored to provide five side wall portions, the two end and the central portions having horizontal slits therein, the end portions being overlapped with their slits registering when the box is erected, and a bottom having side wall portions on opposed edges formed of a blank scored to provide the side wall members, the side wall members having downwardly-projecting tongues struck out therefrom adapted to engage said horizontal slits in said side walls, one of the

tongues being arranged through both slits 15 in the overlapped side wall portions whereby said side is rigidly locked and the bottom is suspended above the lower edge of said side walls, and the side walls are braced and retained in their erected position. 20

In witness whereof, I have hereunto set my hand and seal in the presence of two witnesses.

ALVA L. EAST. [L.S.]

Witnesses:

Miss JOE BRESNAHAN,
DON M. MOON.
